(57) **CLAIM**

The ornamental design for an ink bottle, as shown and described.

DESCRIPTION

FIG. 1 is a front elevational view of a first embodiment of the ink bottle; the opposite side being a mirror image thereof;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view showing a state in which a cap is attached to an upper portion thereof;

FIG. 7 is a right side elevational view showing the state in which the cap is attached to the upper portion thereof;

FIG. 8 is a front elevational view showing the state in which the cap is attached to a lower portion thereof;

FIG. 9 is a right side elevational view showing the state in which the cap is attached to the lower portion thereof;

FIG. 10 is a front elevational view of a second embodiment of the ink bottle; the opposite side being a mirror image thereof;

FIG. 11 is a left side elevational view thereof;

FIG. 12 is a left side elevational view thereof;

FIG. 13 is a top plan view thereof; and,

FIG. 14 is a bottom plan view thereof.

The broken lines showing the state in which the cap is put on the bottle in FIGS. 6 to 9 are for illustrative only and form no part of the claimed design.
